LENS RIM JOINT FOR EYEGLASS FRAMES

Vincent Tanasso, Harrison, and Jacob J. Pomeranz, Brooklyn, N. Y.

Application May 20, 1932. Serial No. 612,444

8 Claims. (Cl. 88—44)

This invention relates to a novel lens rim joint for eye-glass frames; and the invention has reference, more particularly, to joints for discontinuous lens rims provided with novel means to hold the abutting joint elements thereof in operative meeting relation, said means being auxiliary to a fastening screw utilized to secure said joint elements together, and said means being cooperatively related to the fastening screw so as to be held thereby against accidental displacement from its engaged relation to said joint elements.

This invention has for its principal object to provide a novel lens rim joint as above set forth, wherein a novel auxiliary holding means not only serves to initially retain the lens rim closed around a lens pending the setting of a fastening screw in connection with the rim joint elements, but also becomes interlocked with the inserted fastening screw in a novel manner, so that all parts are securely maintained in cooperative relation against accidental loosening, thereby assuring a strong and durable structure easily capable of withstanding the stresses and strains consequent upon the use and handling of the eyeglasses by the wearer thereof.

Other objects of this invention, not at this time more particularly enumerated, will become apparent in the following detailed description of the same.

Illustrative embodiments of this invention are shown in the accompanying drawing, in which:—

Fig. 1 is a front face view of an eye-glass frame of the folding Oxford type, having, in association with the bridge anchor connections to the rims, the novel rim joint structure according to this invention; Fig. 2 is a fragmentary front face view of the novel rim joint structure, drawn on an enlarged scale; Fig. 3 is a top plan view of the parts shown in Fig. 2; Fig. 4 is a vertical longitudinal section through the parts shown in Fig. 2; Fig. 5 is a fragmentary transverse section, taken on line 5—5 in Fig. 2, but drawn on a further enlarged scale; Fig. 6 is a part elevation and part section, taken on line 6—6 in Fig. 5; and Fig. 7 is a perspective view of a modified form of the auxiliary holding means forming a part of the lens rim joint structure.

Similar characters of reference are employed in the hereinabove described views, to indicate corresponding parts.

Referring to the drawing, the reference character 10 indicates the lens rims of an eye-glass frame, which for purposes of illustration, is shown in the folding form commonly known as the Ox-

ford type. Each rim is discontinuous, i. e. the same is provided with separable meeting ends provided with joint means for securing said ends together when the rim has been assembled around and in holding relation to the periphery of a lens 11. Fixedly connected to and flush with the respective ends of the discontinuous rim 10 are radially projecting end lugs 12 and 13, the opposed faces of which are adapted to engage in meeting relation when the ends of the rim are closed together, to thereby contract the rim in embracing and holding relation about the periphery of a lens 11 to be supported thereby. One end lug, as 12, is provided with a screw-threaded opening 14, entering longitudinally therewith from the inner face thereof. The other end lug, as 13, is provided with a smooth bore opening 15 extending longitudinally therethrough, in such position as to align itself with said threaded opening 14 when the end lugs 12—13 are brought together in meeting relation to close the rim 10.

When utilizing the rim joint structure in connection with eye-glass frames of the folding types, such as Oxford, lorgnettes and similar frames, the end lug 12 has in association therewith a spring biased pivotal anchor connection for operatively connecting the rim to an end of a spring bridge 16, whereby the latter is adapted to be connected to and between a pair of lens rims 10 included in the eye-glass frame. Preferably, this anchor connection comprises a chambered stationary hinge butt 17 fixedly attached to the rim 10 and to the rear end of said lug 12, the same having perforate sides to pass a hinge pin 18 therethrough. Cooperating with said hinge butt 17 is a hinge yoke 19, the perforate ears 20 of which are disposed over the perforate sides of said hinge butt 17 so as to be pivotally engaged by the hinge pin 18, when the latter is inserted through the thus assembled parts. Said hinge yoke 19 possesses a tubular extension 21 within which is received and secured an end of the bridge 16. Said hinge butt 17 is provided with a transverse shoulder 22 which is normally engaged by a cooperating transverse shoulder 23 with which said hinge yoke 19 is provided, thus providing stop means for determining the normal out-swung position of the rims 10 relative to the bridge 16, when the foldable eye-glass frame is arranged in open or unfolded condition ready for application to the wearer's nose and eyes. Said rims are yieldably maintained in such out-swung position by a coil spring 24 which is engaged around the hinge pin 18 within the chambered hinge butt 17 and between the sides

thereof. One terminal arm 25 of said spring engages the top wall of said hinge butt 17, and the other terminal arm 26 of said spring engages the top wall of hinge yoke 19.

5 The novel auxiliary holding means cooperative with end lugs 12-13 of the rim 10 comprises a stirrup member which, in a simple form consists in side walls 27 and an end wall 28. The free ends of the side walls 27 are perforated, and 10 extend between the ears 20 of the hinge yoke 19 and the outer sides of the hinge butt 17 so as to be pivotally connected to and upon the hinge pin 18, whereby the stirrup member is capable of swinging movement, which in downward direction will engage the same around the closed together end lugs 12-13 so as to embrace and hold the same against separation, but which in upward direction will be disengaged 15 from such embracing and holding relation to the closed together end lugs so as to free the latter for separation, when it is desired to open the rim 10 for the insertion or removal of a lens 11 therefrom. While I have specified the stirrup member as pivotally connected at and by means 20 of the hinge pin 18, which arrangement is desirable in folding types of eye-glass frames, it is not essential, particularly in types of frames other than the folding types, that such specific pivotal location and means be used; and consequently it is pointed out that, in its broader aspects, this invention contemplates any suitable 25 location of the stirrup member pivoting point, so long as such point as may be selected will permit of sufficient swinging movement thereof to assure its enveloping engagement with and its disengagement from the closed together end lugs 12-13 of the rim 10. The end wall 28 of 30 said stirrup member is provided with an opening 29 alignable with the openings of the end lugs 12-13, and of a diameter corresponding to the head 30 of a fastening screw 31, so as to be capable of receiving said head 30 therein. Leading from said opening 29 outwardly and through 35 the lower margin of said end wall 28 is an open way 32 of a width corresponding to and adapted to pass the shank of said fastening screw 31. Attention may be called to the fact that the form of the stirrup member is subject to more or less variation. For example, in Fig. 7 there is 40 shown a form thereof which includes, in addition to the side walls 27 and end wall 28, a top wall 33; thus producing a closed box-like form, as distinguished from the open loop-like form of stirrup member first described.

45 When the end lugs 12-13 are closed together to contract the rim 10 about the periphery of a lens 11, the stirrup-member is swung down to extend around the closed end lugs, with the end wall 28 abutting the outer face of the end lug 13, thereby holding the rim 10 against opening. When the stirrup member is thus brought into 50 holding relation to the end lugs 12-13, the shank of the fastening screw 31 is passed through the aligned openings of the stirrup member end wall and the end lug 13 so as to screw into the end lug 12, until the head 30 of said fastening screw 31 abuts the outer side of said end lug 13, thus further securing the end lugs together. The head 30 of said fastening screw 55 31 will enter the opening 29 of the stirrup member end wall 28, thereby serving as a key to secure the stirrup member against accidental up-swinging movement and consequent release from operative embracing relation to the closed together end lugs 12-13.

The embrace of the down-swinged stirrup member envelopes the closed together end lugs 12-13 so as to hold the same against separation and consequent opening of the rim 10 with risk of displacement of a lens 11 pending the setting of 80 the fastening screw 31. This offers a great convenience to the operator, since it affords a very efficient temporary holding of the parts against displacement from desired assembled relations while the operator applies and screws home the 85 fastening screw to finally and fully secure the assembly. Furthermore, the embrace of the stirrup member about the end lugs 12-13 after the screw is set, prevents any vibration between the end lugs which might tend to loosen the screw. 90

Should it be desired to open a rim 10 for the removal and replacement of lens 11 relative thereto, all that is necessary to be done is to back out the fastening screw 31 sufficiently far to withdraw the head 30 thereof from the opening 95 29 in the end wall 28 of the stirrup member, thus releasing the latter subject to up-swinging movement. When the fastening screw 31 is sufficiently backed out, and the stirrup member up-swinged, the shank of the screw will be cleared by the withdrawal of the open way 32 of the end wall 28 past the same, so that such up-swinging movement is not impeded. When the stirrup member is thus up-swinged out of holding relation to the end lugs 12-13 of the rim 10, and the screw sufficiently loosened, the ends of the rim may spread apart to sufficiently open up the same for the removal and replacement of the lens 11, without necessity for entirely removing the screw. 100

We are aware that many changes could be 110 made in the above constructions, and many apparently widely different embodiments of this invention could be made without departing from the scope thereof as defined in the hereinafter claims. It is therefore intended that all matter contained in the above description or shown in the accompanying drawing shall be interpreted as illustrative and not in a limiting sense. 115

We claim:—

1. Lens rim joint structure for eye-glass 120 frames, comprising a discontinuous rim having meeting end lugs, said end lugs having alignable openings to receive a fastening screw, a headed fastening screw engageable with said end lugs, a pivoted stirrup member movable into embracing 125 and holding relation to said end lugs when the same are closed together, and an end portion of said stirrup member having an opening sized to receive the head of said screw when the latter is screwed home relative to said end lugs, whereby 130 said stirrup member is locked against displacement from operative embracing and holding relation to said end lugs.

2. Lens rim joint structure for eye-glass 135 frames, comprising a discontinuous rim having meeting end lugs, said end lugs having alignable openings to receive a fastening screw, a headed fastening screw engageable with said end lugs, a pivoted stirrup member movable into embracing 140 and holding relation to said end lugs when the same are closed together, an end portion of said stirrup member having an opening sized to receive the head of said screw when the latter is screwed home relative to said end lugs, whereby 145 said stirrup member is locked against displacement from operative embracing and holding relation to said end lugs, and said end portion of said stirrup member having an open way leading 150 downwardly out of its screw head receiving opening sized to straddle and pass the shank

- of said screw when the latter is loosened sufficiently to withdraw its head from said stirrup member opening, thereby to release said stirrup member for displacement from embracing and holding relation to said end lugs. 80
3. In folding eye-glass frames having discontinuous lens rims, a joint structure for said rims, comprising meeting end lugs, a headed fastening screw engageable with said lugs to secure the same in closed meeting engagement, a fixed hinge butt behind one of said lugs, a hinge yoke to engage an end of the spring bridge of the eye-glass frame, a hinge pin to pivotally couple said hinge yoke and hinge butt, a stirrup member also pivotally connected with said hinge pin, said stirrup member being movable into embracing and holding relation to said end lugs when the same are closed together, and an end portion of said stirrup member having an opening sized to receive the head of said screw when the latter is screwed home relative to said end lugs, whereby said stirrup member is locked against displacement from operative embracing and holding relation to said end lugs. 85
- 10 4. In folding eye-glass frames having discontinuous lens rims, a joint structure for said rims, comprising meeting end lugs, a headed fastening screw engageable with said lugs, a chambered hinge butt fixed to a rim behind one of said lugs, a hinge yoke having perforate ears to straddle said hinge butt and a socketed free end to which an end of a spring nose-bridge is anchored, a hinge pin engaged through said hinge yoke ears and hinge butt, cooperative stop-means connected with said hinge yoke and hinge butt, spring means housed in said hinge butt to yieldably retain the latter and said hinge yoke in normal stopped relation, a stirrup member having side arms disposed between said hinge yoke ears and hinge butt and pivotally mounted on said hinge pin, said stirrup member being movable into embracing and holding relation to said end lugs when the same are closed together, the free end portion of said stirrup member having an opening sized to receive the head of said screw when the latter is screwed home relative to said end lugs, whereby said stirrup member is locked against displacement from operative embracing and holding relation to said end lugs, and said end portion of said stirrup member having an open way leading downwardly out of its screw head receiving opening sized to straddle and pass the shank of said screw when the latter is loosened sufficiently to withdraw its head from said stirrup member opening, thereby to release said stirrup member for displacement from embracing and holding relation to said end lugs. 90
- 15 5. In folding eye-glass frames having discontinuous lens rims, a joint structure for said rims, comprising meeting end lugs, a headed fastening screw engageable with said lugs, a chambered hinge butt fixed to a rim behind one of said lugs, a hinge yoke having perforate ears to straddle said hinge butt and a socketed free end to which an end of a spring nose-bridge is anchored, a hinge pin engaged through said hinge yoke ears and hinge butt, cooperative stop-means connected with said hinge yoke and hinge butt, spring means housed in said hinge butt to yieldably retain the latter and said hinge yoke in normal stopped relation, a stirrup member having side arms disposed between said hinge yoke ears and hinge butt and pivotally mounted on said hinge pin, said stirrup member being movable into embracing and holding relation to said end lugs when the same are closed together, and the free end portion of said stirrup member having an opening sized to receive the head of said screw when the latter is screwed home relative to said end lugs, whereby said stirrup member is locked against displacement from operative embracing and holding relation to said end lugs. 95
- 20 6. In folding eye-glass frames having discontinuous lens rims, a joint structure and nose-bridge connection for said rims, comprising meeting end lugs, a headed fastening screw engageable with said lugs, a chambered hinge butt fixed to a rim behind one of said lugs, a hinge yoke having perforate ears to straddle said hinge butt and a socketed free end to which an end of a spring nose-bridge is anchored, a hinge pin engaged through said hinge yoke ears and hinge butt, cooperative stop-means connected with said hinge yoke and hinge butt, spring means housed in said hinge butt to yieldably retain the latter and said hinge yoke in normal stopped relation, a stirrup member having side arms disposed between said hinge yoke ears and hinge butt and pivotally mounted on said hinge pin, said stirrup member being movable into embracing and holding relation to said end lugs when the same are closed together, the free end portion of said stirrup member having an opening sized to receive the head of said screw when the latter is screwed home relative to said end lugs, whereby said stirrup member is locked against displacement from operative embracing and holding relation to said end lugs. 100
- 25 7. A joint for discontinuous lens rims of eye-glass frames, comprising radially projecting end lugs adapted to meet when the rim is closed, a headed fastening screw engageable with said lugs, a pivoted stirrup member to extend around said lugs when the latter are closed together, and said stirrup member having means engageable by said screw to positively lock the stirrup member from displacement relative to said lugs. 105
- 30 8. A joint for discontinuous lens rims of eye-glass frames, comprising radially projecting end lugs adapted to meet when the rim is closed, a fastening screw engageable with said lugs, a member to extend around said lugs when the latter are closed together, and said member having means engageable by said screw to positively lock the member from displacement relative to said lugs. 110
